US0D1025064S

(12) **United States Design Patent** (10) **Patent No.:** **US D1,025,064 S**
(45) **Date of Patent:** **** Apr. 30, 2024**

(54) **KEYBOARD**

(71) Applicant: **Logitech Europe S.A.**

(72) Inventors: **Yi-Hsuan Lin**, New Taipei (TW); **Blaithin Crampton**, County Meath (IE); **Marcel Twohig**, County Cork (IE); **Anish Shakthi Ovia Selvan**, County Cork (IE); **Anatoliy Polyanker**, Lausanne (CH); **Jingyan Ma**, Lausanne (CH); **Ming Feng Hsieh**, Hsinchu (TW); **Olivia Hildebrand**, Geneva (CH)

(73) Assignee: **Logitech Europe S.A.**, Lausanne (CH)

(**) Term: **15 Years**

(21) Appl. No.: **29/800,509**

(22) Filed: **Jul. 21, 2021**

(51) **LOC (14) Cl.** **14-02**

(52) **U.S. Cl.**

(57) **CLAIM**

The ornamental design for a keyboard, as shown and described.

DESCRIPTION

FIG. 1 is a perspective front side view of a keyboard showing our new design;

FIG. 2 is a perspective rear side view thereof;

FIG. 3 is a top plan view thereof;

FIG. 4 is a bottom plan view thereof;

FIG. 5 is a rear elevation view thereof;

FIG. 6 is a front elevation view thereof;

FIG. 7 is a left side elevation view thereof; and,

FIG. 8 is a right side elevation view thereof.

The broken lines seen in the drawings depict portions of the keyboard that form no part of the claimed design.

1 Claim, 5 Drawing Sheets
